C. F. TRILL, OF BALTIMORE, MARYLAND.

Letters Patent No. 82,893, dated October 6, 1868.

IMPROVEMENT IN STEAM-GENERATORS.

The Schedule referred to in these Letters Patent and making part of the same.

TO ALL WHOM IT MAY CONCERN:

Be it known that I, C. F. TRILL, of the city and county of Baltimore, and State of Maryland, have invented a new and improved Steam-Generator; and I do hereby declare that the following is a full, clear, and exact description of the construction and operation of the same, reference being had to the accompanying drawings, making a part of this specification, in which—

Figure 1 is a side view, a portion of the walls being removed to show the internal construction.

Figure 2 is a horizontal section through line $z z$ of fig. 1.

Figure 3 is a sectional view of the burner, showing its connection with the feed-pipe and the heating-pipes.

This invention has for its object the construction of a strong and durable steam-generator, to be heated by petroleum or other liquid or gaseous fuel, by an arrangement of devices hereinafter described.

In the drawings, A is the shell of the generator, and $a a$ is a thick covering of strong wire wound tightly and firmly around that portion of it which surrounds the boiler. One or more layers of wire may be employed, and it may extend directly or obliquely around the boiler, and may be crossed and overlaid in any way that may be preferred, for the purpose of augmenting the strength of the walls.

B is the smoke-flue; C C' are the steam-pipes that lead to the steam-gauge, whistle, safety-valve, &c.; and D is the pipe through which the petroleum or gas is fed to keep up the necessary heat.

The interior of the shell A is divided into three compartments, E F G, by means of two strong partitions, H I. The lower apartment, E, is very shallow, being only large enough to accommodate the supply-pipe D and its branches, together with the burners, and being provided with apertures, e e, for the admission of air. The upper part, F, is a little deeper, but is only intended to hold several convolutions of the steam-pipes, and to form a heater in which the hot air rising from the burners shall be collected and applied continuously to a great extent of steam-pipe, so that the heat generated by the burners may be as fully utilized as possible. The central chamber G occupies the greater part of the shell A, being intended to hold the water from which the steam is generated.

The pipe D from the tank or gasometer extends into and directly across the chamber E, and has connected with it a large number of branch pipes, d d, extending at right angles from it all along both sides, to or nearly to the walls A A, and provided at the proper intervals with burners, i i, attached to their upper side.

A series of vertical pipes, J J, is provided within the chamber G, each pipe resting upon the floor H, directly over a burner, or else extending through the floor to a position over the burner, as shown in fig. 3.

When the pipes rest on the floor, an aperture is made through the latter to allow the heat, &c., from the burners to pass up into and through the pipes.

The upper ends of the pipes are firmly fixed to the upper partition I, so that the products of combustion from the burners pass into chamber F, and thence to the open air by means of the flue B.

The water of course occupies the lower portion of chamber G, its upper portion being the steam space. From this space the steam escapes through a series of short pipes, m m m, into a steam-pipe or series of steam-pipes, K K, arranged in chamber F, as shown in the drawings, and convoluted in any manner that may be thought most advantageous for the absorption of the heat from the chamber.

The method which I prefer is that of arranging a series of independent pipes over the spaces between the tops of the rows of pipes J J, as shown in fig. 2, having one end of each pipe, K, closed and the other passing through the wall A and emptying into a curved tubular section, L, from which the steam is conveyed to the cylinder by a pipe, M. In this case, I carry pipe K back and forth in the same vertical plane, as shown in fig. 1, in which figure the four letters K represent but one pipe, it being any one of the pipes K K shown in fig. 2. The generator thus constructed can be made very cheaply, and will be strong and durable. Nearly all the heat of the burners will be utilized, a part of it being confined in chamber E and applied to the bottom of the boiler, and the rest of it being carried up through the pipes J J and applied to the water and steam in chamber G and to the steam-pipes in chamber F.

The lower portion, A', of the shell A is made removable, so that the pipe D and its branches and the

burners can be readily got at for the purpose of cleaning them. The upper part, A'', may also, if preferred, be made removable, so that the various pipes in the upper part of the apparatus can be easily cleaned, and any necessary repairs made.

The weight of a boiler constructed in this manner need not exceed one-fourth of the weight of the common navy boilers of the same solidity and durability, while it occupies much less room and requires less fuel. The wires surrounding the boiler should be as fine as possible.

Having thus described my invention, what I claim as new, and desire to secure by Letters Patent, is—

1. The combination of the boiler A, with the layer or layers of wire α , wound around it, as described.
2. The arrangement, within the steam-generator A, of the chambers E F G, with the pipes D J K and burners γ , substantially as described.

C. F. TRILL.
